UNITED STATES PATENT OFFICE

DE WITT C. EDMONDSON, OF EVANSVILLE, INDIANA.

ROLLER-SUPPORT FOR SLIDING DOORS.

No. 911,554.

Specification of Letters Patent.

Patented Feb. 2, 1909.

Original application filed April 27, 1906, Serial No. 313,937. Divided and this application filed December 24, 1906.
Serial No. 349,256.

To all whom it may concern:

Be it known that I, DE WITT C. EDMONDSON, a citizen of the United States, residing at Evansville, in the county of Vanderburgh and State of Indiana, have invented certain new and useful Improvements in Roller-Supports for Sliding Doors; and I do declare the following to be a full, clear, and exact description of the invention, reference being had to the accompanying drawings, and to the letters and figures of reference marked thereon, which form a part of this specification.

This invention relates to roller supports for edgewise movable doors.

The objects of the invention are to provide improved appliances for supporting sliding doors, particularly car doors; to provide roller supports which may be constructed of metal that will be least liable to break in use and be adapted to be repaired when damaged, and to provide roller supports that may be relied on to operate freely, and be durable and economical in use.

With the above-mentioned and minor objects in view, the invention consists in roller supports for doors of novel construction, and in the combinations and arrangements of elements as hereinafter described and pointed out in the appended claims, said invention having been shown in my application for Letters Patent of the United States, filed April 27, 1906, Serial No. 313,937, this being a divisional application for Letters Patent for certain features not claimed in said prior application.

Referring to the drawings, Figure 1, is a fragmentary side elevation of a box-car body having the improvements applied thereto as illustrating the application and functions thereof; Fig. 2, a fragmentary vertical sectional view on the line A A in Fig. 1; Fig. 3, a fragmentary vertical sectional view on the line B B in Fig. 1; Fig. 4, a fragmentary vertical sectional view showing the lower part of the door and bearing shoe thereof; Fig. 5, a fragmentary vertical sectional view, as at the line C in Fig. 1; Fig. 6, a fragmentary vertical longitudinal sectional view of the lower door rail as on the line D D in Fig. 3; and Fig. 7, a fragmentary vertical sectional view, as at the line E in Fig. 1.

Similar reference characters designate corresponding elements or features in the various figures of the drawings, parts of the car and doors together with certain of the attach-

ments being herein indicated as being advantageously associated with the present invention.

In the drawings, *a* designates a side-sill of the car body; *b*, the siding; *c*, the carfloor; *d*, the roof; and *e* and *f*, the door-posts at opposite sides of a door way of the car, all of ordinary construction.

In practical embodiment, the invention includes a lower door rail *F* which is composed of rolled metal to form a base having bolt-holes *g* and suitably secured against the siding *b* opposite to the side sill *a*, the rail being so formed as to have an inclined guide side *g* adjacent to the siding at an angle to the base, a narrow top *h*, and an outer inclined guide side *i* extending downwardly from the top *h*, all integral, so that the cross-section of the rail resembles that of the frustum of a cone. The top *h* of the rail has a suitable number of apertures *j* therein in which rollers *G* are arranged and mounted on axles *k* that are supported by the inclined guide sides *g* and *i*, the rollers being nearly incased in the hollow rail with the tops of the rollers slightly above the tops *h* of the rail. The axles *k* are held removably in the guide sides *g* and *i* by nuts *l*. An upper guide rail *H* is suitably secured to the side of the car body, the rail having a lip *m* extending downwardly, and a guide-plate *n* is interposed, as shown between the siding *b* and the rail.

The rails *F* and *H* are usually of suitable length so as to accommodate two doors, as shown in Fig. 1, a tight door *I* and a ventilating door *J*. The framing of the doors may be variously constructed, and each door has a grooved bottom in which is a metal shoe *K* having a guide lip *K'* extending over the side *i* of the lower rail while the shoe bears on the rollers *G*. The shoe has also an inner guide lip *K''* extending over the guide side *g* of the rail *F*. Also the shoe is provided with a pair of flanges *O* and *P* which embrace the door to which they are secured for attaching the shoe to the door. The top of each door is provided with a face-plate *L* that has a flange *q*.

In order to effectually retain the car doors on the lower rail a pair of substantial stops *M* and *N* are secured to the side of the car body at the ends of the door rails. The doors have handles *r*. The lower rail is secured in the desired position by bolts *s*.

In practical use, the doors will move

easily on the rollers and advantageous results attained by the above-described construction will be fully understood as being obvious from the detailed description of 5 construction, suffice it to say that cost charges for lost car doors may be avoided by the use of the invention.

Having thus described the invention, what is claimed as new is—

- 10 1. A door rail comprising a base with bolt-holes therein, a flat inner guide side extending from the base at an obtuse angle, a flat top extending at an obtuse angle from the guide side, and a flat outer guide side 15 extending from the top at an obtuse angle.
2. The combination with a car body side, of a lower door rail comprising a base attached to the body side, an inner guide side extending upward from the base at an obtuse angle thereto and away from the body side and having openings therein to receive axles, a top extending from the guide side and away from the car body side and having apertures therein, an outer guide side 20 extending from the top downward and outward therefrom to receive axles, axles mounted in the openings of the guide sides, and rollers mounted on the axles 25 extending from the top downward and outward therefrom and having openings therein to receive axles, axles mounted in the openings of the guide sides and extending under said top, and rollers mounted on the axles

between the guide sides and protruding 30 through the apertures of the top.

3. The combination with a car body side, and a door having two oppositely-inclined guide lips on the bottom thereof, of a lower door rail comprising a base attached to the 35 body side, an inner guide side extending upward from the base at an obtuse angle thereto and away from the body side to guide one of the guide lips of the door and having openings therein to receive axles, a 40 top extending from the guide side and away from the body side and having apertures therein, an outer guide side extending from the top downward and outward therefrom to guide the other guide lip of the door and 45 having openings therein to receive axles, axles mounted in the openings of the guide sides, and rollers mounted on the axles between the guide sides and protruding 50 through the apertures of the top to support the door.

In testimony whereof, I affix my signature in presence of two witnesses.

DE WITT C. EDMONDSON.
